UNITED STATES PATENT OFFICE

2,453,278

GRAIN DRIER

Robert J. Staples, Sr., and Henrietta Staples,
Houston, Tex.

Application November 13, 1945, Serial No. 628,208

4 Claims. (Cl. 34—102)

1

This invention relates to a grain drier.

An object of the invention is to provide equipment of the character described embodying a closed body having a drying chamber therein with a hopper, or hoppers, at the top of the body, means for conveying the grain to be dried through the chamber and with a discharge outlet at the bottom of the chamber.

Another object of the invention is to provide a grain drier of the type above specified equipped also with a conveyor leading from said discharge outlet and arranged to deliver the discharged grain back into a hopper at the top of the body whereby the grain may be rerun through the chamber if not sufficiently dried on the first run.

It is a further object of the invention to provide a grain drier of the character described comprising a body which contains a closed chamber and whose cover is formed into hoppers, preferably two, with a series of upper, intermediate and lower conveyors through the chamber with chutes leading from the hoppers to the upper conveyor and with chutes leading from the upper conveyor to the intermediate conveyors and from the intermediate conveyors to the bottom conveyor with a discharge chute leading from the bottom of this last conveyor and with an elevating conveyor leading from the discharge chute and discharging the grain back up into one of said hoppers to be rerun with means for heating said chamber.

The drier has been specially designed to be mounted on a vehicle whereby the conveyors may be driven from the vehicle motor and the drier readily transported from place to place.

With the above and other objects in view the invention has particular relation to certain novel features of construction, operation and arrangement of parts, an example of which is given in this specification and illustrated in the accompanying drawings, wherein:

Figure 1 is a longitudinal, vertical, sectional view, partly broken away.

Figure 2 is a plan view of the drier as mounted on a vehicle.

Figure 3 is a vertical, sectional view taken on the line 3-3 of Figure 1 and partly broken away.

Figure 4 is an end view shown partly broken away.

Referring now more particularly to the drawings wherein like numerals of reference designate the same parts in each of the figures, the numeral 1 designates a closed body containing the drying

2

chamber 2. In the present illustration the top of the body is closed by the hoppers 3, 3 arranged alongside and which terminate, at the bottom, in the longitudinal troughs 4, 4 extending from end to end of the respective hoppers. In these troughs are the spirals 5 which are fixed on the shafts 6, 6, said troughs, spirals and shafts forming conveyors arranged to convey the grain in the respective hoppers toward the discharge ends 10 of said troughs.

Leading from said discharge ends are the downwardly converging chutes 7, 7.

At one end of the body the shafts 6 project beyond said body and said projecting ends have the sprocket wheels 8, 8 fixed thereon over which the driving sprocket chains 9, 9 operate and these sprocket chains also operate over corresponding sprocket wheels 10, 10 which are loosely mounted on the projecting end of a longitudinal shaft 11 mounted in the body. The sprocket wheels 10 may be alternatively clutched with the shaft 11 by means of a jaw clutch 12 which is splined on said shaft and which may be operated by the clutch lever 13 so that conveyors at the bottom of the respective hoppers may be alternatively driven and grain delivered from one hopper or the other as desired.

Fixed on the shaft 11 there is a spiral 14 which rotates in a trough 15, into one end of which 30 the chutes 7 discharge. Leading from the other end of the trough 15 there is a chute 16 and beneath this chute 16 there is a trough 17. In the trough 17 there is an axial shaft 18, one end of which projects beyond the body 1 and has the sprocket wheels 19 and 20 fixed thereon. Fixed 35 on the shaft 11 and aligned with the sprocket wheel 19 there is a sprocket wheel 21 and over the sprocket wheels 19 and 21 the sprocket chain 22 operates and transmits rotation from the former to the latter.

Fixed on the shaft 18 there is a conveyor spiral 23 by means of which the grain is conveyed along the trough 17 toward the outlet end thereof. Leading from this outlet end there 45 is a chute 25 and beneath the trough 17 there is a trough 26 in which an axial shaft 27 is mounted. One end of this shaft 27 extends beyond the body and has a sprocket wheel 28 fixed thereon which is aligned with the sprocket wheel 20 and a sprocket chain 29 operates over said wheels and transmits rotation from the former to the latter. Also fixed on the shaft 27 there is a sprocket wheel 30 and within the trough 26 and fixed on said shaft there is the spiral 31. 50 This spiral moves the grain along the trough 26

toward the discharge end thereof and leading from said discharge end there is a discharge chute 32 and beneath chute there is a trough 33 into which the grain is delivered through the chute 32.

Mounted in the trough 33 there is an axial shaft 34 on which the spiral 35 is fixed. One end of the shaft 34 projects beyond the body and has a sprocket wheel 36 fixed thereon which is aligned with the sprocket wheel 30 and a sprocket chain 37 operates over these sprocket wheels and transmits rotation from the former to the latter. Also fixed on the shaft 34 there is a sprocket wheel 38.

Beneath the trough 33 there is a trough 39 and leading from the discharge end of the trough 33 into the inlet end of the trough 39 there is a chute 40.

Mounted axially in the trough 39 there is a shaft 41, one end of which is extended beyond the body and fixed on said extended end are the sprocket wheels 42, 43. The sprocket wheel 42 is aligned with the sprocket wheel 38 and operating over them is the sprocket chain 44 which transmits rotation from the former to the latter. The numeral 45 designates a driving shaft which may be connected with the motor of the vehicle by means of which the drier is transported and this shaft 45 has the sprocket wheel 46 fixed thereon and aligned with the sprocket wheel 43 and a sprocket chain 47 operates over these aligned sprocket wheels and transmits rotation from the wheel 46 to the wheel 43.

Fixed on the shaft 41 within the trough 39 there is a spiral 48 which moves the grain along said trough from its inlet end to its discharge end and leading from the discharge end thereof there is a down spout 49 which has the branches 50, 50 through which the dried grain may be discharged into sacks. These branches are controlled by the valve 51 by means of which they may be alternatively opened and closed. The down spout 49 is also provided with a gate valve 52 by means of which it may be completely closed if it be desired to rerun the grain through the drier.

The shafts 6, 11, 18, 27, 33, 41 and 45 are mounted to rotate in suitable bearings in the body at the ends of the respective troughs and it will be noted that the troughs through the chamber are open above so as to expose the grain to the warm air in the chamber and it will be noted that the grain will be moved back and forth along said troughs from the inlet thereof into the trough 45 until the discharge thereof from the trough 39 and the grain being moved along said troughs will be agitated by the conveyor spirals so as to expose it to the heated air in said chamber.

It may be found necessary to rerun the grain in case it has not been sufficiently dried by one run through the drying chamber. For that reason an elevating tube 53 has been provided alongside the body. Its lower end is connected into the down spout 49 above the gate valve 52. It has an axial shaft 54 mounted to rotate in end bearings carried by the tube and fixed on this shaft 54 is the elevator spiral 55. The elevator tube 53 terminates in a downwardly directed chute 56 which is arranged to discharge grain into the adjacent hopper 3. The end of the shaft 41, adjacent the down spout 49 is extended and fixed thereon there is a bevel gear wheel 57 which is in mesh with and drives a similar bevel gear wheel 58 which is fixed on one end of a stub shaft 59. This stub shaft is mounted to rotate in a

suitable bearing in a bracket 60 which may be fixed to the down spout 49. The other end of the shaft 59 has a sprocket wheel 61 fixed thereon which is aligned with a similar sprocket wheel 62 which is fixed on the lower end of the shaft 54 and operating over these sprocket wheels 61 and 62 and transmitting rotation from the former to the latter there is a sprocket chain 63.

Should it be desired to rerun the grain the gate valve 52 may be closed and the grain will then be picked up from the down spout 49 and elevated through the tube 53 and discharged into the adjacent hopper 3. The clutch 42 may then be suitably manipulated to operatively connect the corresponding shaft of this hopper with the driving mechanism and the grain redelivered to said hopper will then be passed through the drier from trough to trough from above, downwardly as hereinabove indicated.

As indicated in Figure 3 the conveying troughs are arranged in diagonal relation from above, downwardly so that the lower or discharge trough will be arranged alongside the side wall of the body and arranged underneath the series of conveying troughs there is a suitable heater 64 containing a gas burner 65 which may be supplied with gas from a tank 66 mounted on the outside of the chamber. However any suitable type of heating equipment may be provided.

There is a hinged door 67 mounted in one side of the body and normally held closed by a latch 68 whereby access may be obtained to the interior of the drying chamber.

It will be noted that all of the troughs beneath the hoppers are located wholly within the drying chamber and are open so as to give a maximum exposure to the grain, or other material passing along the troughs.

The drawings and description are illustrative merely while the broad principle of the invention will be defined by the appended claims.

What we claim is:

1. A grain drier comprising, a closed body containing a drying chamber, hoppers forming the top of the body and extending from end to end thereof, a conveyer in each hopper, a series of conveyors extending across said chamber and arranged in diagonal relation from above downwardly with the drying chamber beneath said series, a chute leading from an upper to a lower conveyor, a chute leading from each hopper to the upper conveyor, discharge means leading from the lower conveyor, a conveyor leading from said discharge means and arranged to convey grain from the discharge means into one of the hoppers and means for heating the chamber.

2. A grain drier comprising, a closed body containing a drying chamber, a pair of hoppers forming the top of the chamber, a single series of troughs across the chamber and arranged in diagonal relation at different elevations, conveying means in the hoppers and in the troughs whereby material to be dried may be delivered from a selected hopper to a trough and from trough to trough from above downwardly, an outlet leading from the bottom trough, means for closing said outlet, an elevator leading from the outlet and arranged to return the material delivered to the outlet into one of the hoppers.

3. A drier for grain and similar material comprising, a closed body having a drying chamber therein, hoppers on the body, a single series of open troughs in diagonal relation and at different elevations in the chamber beneath the hoppers, chutes leading from the hoppers into one of said

troughs, means for causing movement of material, alternatively, from the hoppers through said chutes to the corresponding trough, means for moving said material from the last mentioned trough through the other troughs successively, a discharge chute leading from the final trough and means for heating the chamber.

4. A drier for grain and similar material comprising, a closed body having a drying chamber therein, hoppers on the body and extending from end to end thereof, a single series of troughs in the chamber beneath the hoppers arranged in diagonal relation from above downwardly and disposed above said chamber, chutes leading from the hoppers into one of said troughs, means for causing movement of material, alternatively, from the hoppers through said chutes to the corresponding trough, means for moving said material from the last mentioned trough through the other troughs successively, a discharge chute 10 15 20

leading from the final trough, means for driving said moving means and means for heating the chamber.
